REFRIGERATOR BOX

Joseph H. Orley, Detroit, Mich.

Application February 18, 1944, Serial No. 522,882

1 Claim. (Cl. 312—174)

This application relates to refrigerators and discloses a novel shelf construction in an open top refrigerator.

The appended drawing diagrammatically shows the shelf construction. In this drawing Figure 1 is a vertical sectional view with the top cover closed, and Figure 2 is a similar view with the top cover raised or partly open. Fig. 3 is a horizontal sectional view taken on line 3—3 of Fig. 1 and Fig. 4 is a partial end elevation of the shelf sections.

The refrigerator herein shown in the various views comprises an open top receptacle 10 having a top cover 11, horizontally hinged at 12 at its rear edge to swing up and down. Midway of and across the receptacle is a two-section shelf of heat insulating construction of which the rear section 14 is stationary, and of which the forward section 15 is movably mounted. The rear shelf section 14 is seated upon flanged bracket 23 and may be received along its side edges in any well known manner as described. For example, additional flanged brackets such as brackets 23 may be used.

The means for movably mounting the forward section consists of a plurality of links comprising, at each side of the shelf, link 16, which movably connects the rear edges of the two shelf sections, the link 17 which movably connects the forward edges of the two sections, and the link 18 which movably connects the forward edge of the forward section 15 to the pivot 22 on the top cover. Each link 16 and 17 is pivotally connected to the two sections of the shelf by means of inwardly turned ends thereof inserted in sockets thereof in edge portions of said shelves. Link 18 is similarly connected to the forward section. A flange 19 of the rear section 14 is over-lapped by flange 24 on the rear edge of the forward section to provide a stationary support for the rear edge of the forward section, and a flange 21, secured to the interior of receptacle 10, receives flange 25 on the forward edge.

It will be observed from Figure 1 that when the top cover 11 is swung down, the two sections of the shelf form a continuous shelf midway of and across the receptacle, dividing the receptacle into an upper and a lower portion and providing a heat insulating barrier between the upper and lower portions whereby the lower portion may be maintained at a considerably lower temperature than the portion above the shelf; however, when 5 the top 11 is swung up, the shelf section 15 is raised and supported by the top cover to provide access into the lower portion of the refrigerator, even below the shelf section 14, through the opening 20 normally occupied by the forward section 15 of the shelf, and also providing access to the shelves themselves and any goods thereon.

Now having described the refrigerator construction herein shown, reference should be had to the claim as follows.

20 I claim:

A receptacle having a top cover horizontally hinged on its rear edge to swing up and down, a two section shelf midway of and across the receptacle below the open top, the rear section being stationary, and means for mounting the forward section, comprising a link movably connecting the rear edges of the forward and rear sections and a link movably connecting the forward edges of the forward and rear sections, and a link movably connecting the forward edge of the forward section to the top cover, whereby the two sections may be aligned to form one complete shelf when the top cover is down, and the forward section is raised to be above the rear section when 25 the top cover is raised, to provide access to the receptacle below the rear section through the space normally occupied by the forward section, the rear edge of the forward section being supported by the front edge of the rear section, when 30 the cover is down.

JOSEPH H. ORLEY.
